TOTALIZER CLEAR SIGNAL.

1,426,377.

Specification of Letters Patent. Patented Aug. 22, 1922.

Application filed February 10, 1919. Serial No. 276,172.

To all whom it may concern:

Be it known that we, HYMAN GOLBER and ARTHUR F. POOLE, citizens of the United States, residing at Chicago, Illinois, and 5 Kenilworth, Illinois, respectively, have invented a certain new and useful Improvement in Totalizer Clear Signals, of which the following is a specification.

Our invention is an improvement in totalizer clear signals for calculating machines and is especially designed for use in the particular variety of calculating machines known as the Wahl adding and subtracting typewriter extensively marketed by 10 the Remington Typewriter Company, the structure of which is described in numerous issued patents, for example Patent No. 893,719, July 21, 1908, John C. Wahl, Patent No. 1,270,471, June 25, 1918, John 15 C. Wahl, Patent No. 1,148,733, Aug. 3, 1915, John C. Wahl.

Numbers are inserted in the Wahl machine by means of the numeral keys of the typewriter, there being ordinarily ten of 20 such numeral keys, and vertical motion of said keys is by appropriate mechanism translated into differential rotation of a certain wheel, known as the master wheel. The totalizer of the Wahl machine is 25 mounted upon a traveling truck, moving synchronously with the carriage of the typewriter, and in order to insert a number in the machine this carriage is first tabulated to the decimal place corresponding to the 30 first significant digit of said number, and the number is then inserted in the machine one digit at a time. As each digit key is 35 depressed, the master wheel rotates a number of places, corresponding to said key, and inserts the required digit into the 40 proper decimal place of the totalizer. After each digit is inserted, the typewriter carriage advances one step to the left, thus bringing the master wheel into engagement 45 with the next lower decimal order of the totalizer, and the next digit of the number is inserted in said place. This operation is continued, one digit at a time being inserted into the totalizer until the entire 50 number has thus been inserted. The mechanism by which the vertical motion of the digit keys is translated into a differential rotation of the master wheel has been thoroughly described in the cited patents to

Wahl, and since said mechanism is no part 55 of our present invention, it is not necessary to describe it in detail in this place.

The Wahl machine is equipped with a reversing device by means of which numbers may be inserted either in addition or 60 in subtraction. This reversing device usually consists of a gear shift between the digit keys and the master wheel, to the end that when the shift is in one position,—the addition position,—the master wheel 65 will rotate in a counterclockwise direction. When the reversing device is put in its subtraction position, the vertical motion of the numeral keys will result in a clockwise differential rotation of the master wheel and 70 thus numbers will be inserted into the totalizer in a subtracting direction. This reversing mechanism is also described in the cited patents to Wahl and inasmuch as it forms no part of our present invention, need 75 not be described in detail here.

In the Wahl machine numbers are inserted in the machine in an addition direction and the total of these numbers is 80 visibly exhibited in the totalizer. When it is desired to clear the machine, that is, write the exhibited total on the worksheet, the gear shift is thrown to its subtracting 85 position and the numeral keys are operated in a sequence determined by the exhibited total. This results in subtracting the exhibited total from the totalizer, which, if the operation has been correctly performed, then stands at zero.

Inasmuch as the Wahl machine has no operation corresponding to the automatic extraction of a total, that is, totals must be extracted from the Wahl totalizer by the process of copying the total as just described, it sometimes happens that the operator either misreads the total exhibited by the totalizer, or operates the wrong digit keys and thus an amount is left in the totalizer when the totalizer should stand at zero or be clear. Accordingly when the 90 next computation is made in the machine if it is not noticed that the totalizer is not standing clear before the beginning of the computation a wrong computation will result, since the number standing in the totalizer will be added to the numbers inserted therein.

The object of our invention is to pro-

vide a safeguard against the above described misoperation of the Wahl machine, and in carrying out our invention we provide a special key on the typewriter which 5 is adapted to print a star or other characteristic mark and also adapted to be operated in the decimal place to the right of the lowest decimal place of the totalizer. In the event that the totalizer stands clear, 10 this extra key, which we shall hereinafter call the star printing key, may be operated without interference. However, if the totalizer does not stand at clear and it is attempted to operate this star printing key, 15 then the machine will be locked up and the operator's attention will at once be called to the error which has just been made. A further object of our invention is the provision of a totalizer clear signal which 20 will use a great number of parts which are already in the Wahl mechanism, thereby enabling our device to be used with Wahl machines which are already in existence. Another object of our invention is the 25 provision of a totalizer clear signal, the mechanism for which shall be almost exclusively in the totalizer itself, thereby permitting the use on the same machines of totalizers equipped with our improved clear 30 signal and totalizers not so equipped.

35 A further object of our invention is to provide a totalizer clear signal which will be simple and efficient in its operation and consist of but a few easily made parts.

40 Further objects of our invention will be hereinafter described in the specification and will appear in the claims.

Referring now to the figures:

Fig. 1 is a sectional view of a Wahl machine equipped with our improved mechanism;

Fig. 2 is a section along the line 2—2 of Fig. 1;

Fig. 3 is a rear view of the totalizer with much of the mechanism removed;

Fig. 4 is a perspective view of certain details;

Fig. 5 is a perspective view of the totalizer clear signal as it is in cooperation with certain parts of the actuating mechanism, and

Fig. 6 is a view of the type bar for the star printing key.

Referring to Fig. 1: The totalizer 10 is mounted on a truck 11, which, as is customary in the Wahl machines, moves step by step to the left in synchronism with the motion of the typewriter carriage. The totalizer 10 contains the customary carrying gears 12, carrying mechanism 13, intermediate gears 14 and number wheels 15, all of which are old and common to the Wahl totalizers of the prior art. The number wheels 15 are rigidly mounted to gears 16, each one of 105 which is equipped with a short tooth 17,

which is adapted to be operated on by the prong 20 of a comb 18, rotatably mounted in the framework of the totalizer on a shaft 19. By reference to Fig. 5, it will be seen that each numeral wheel is equipped with a gear 16 containing a short tooth 17, and that cooperating with each of these wheels there is a comb tooth 20. The comb 18 is urged into engagement with the gears 16 by means of a spring 21, which is mounted on the framework of the totalizer. The short teeth 17 of the gears 16 are so placed in reference to the numeral wheels 15 that when the 0 is opposite the sight window 22 in the totalizer casting 23 the short tooth 17 will be in a position 20 to be engaged by the comb 18. From this arrangement it obviously results that when the totalizer stands at zero all of the short teeth 17 are in position to be engaged by the comb 18, and said comb will move in a 25 counterclockwise direction (Fig. 1) until it is stopped by contact of the prongs 20 with the short teeth 17. If the totalizer does not stand at zero, the fact of any of the long teeth of the gear 16 contacting with any of the prongs 20 will serve to hold the comb against the tension of the spring 21 in the position shown in Fig. 1.

Rigid with the comb 18 is an arm 24, adapted to operate a lever 25, which is rotatably mounted on a stud 26, in the side plate 69 of the totalizer and is urged to rotate in a clockwise direction by a spring 27 extending between the lever 25 and a stud 28 in the totalizer side plate 69. The lever 25 is provided with a latch 29, which is adapted to engage a lever 30 rotatably mounted on the shaft 31, which also serves to support one set of the swinging arms 32 customarily present in the Wahl totalizer. The lever 30 is given a tendency to rotate about the shaft 31 in a counterclockwise direction (Fig. 5) by a spring 33 extending between said lever and shaft 34 in the framework of the totalizer.

From the above description it will be obvious that if the totalizer does not stand at zero and the lever 30 be lifted from its normal position, shown in Fig. 1, that said lever will be held in its elevated position by the latch 29. However, if the totalizer stands at zero when the lever 30 is lifted, then the lever 25 will be held in the position shown in Fig. 1, and the lever 30 is free to return to its normal position. In our machine, therefore, we have this condition: That the fact of the totalizers standing at zero permits the lever 30 to be lifted and returned to its normal position without interference. However, if the totalizer does not stand at zero and the lever 30 be lifted, then it will be caught on the latch 29 and will not be able to return to its normal position shown in Fig. 1. It is to be noted that the normal position of the lever 25 is determined by its 110

contact with the surface of the comb 18, and that the normal position of the lever 30 is determined by its contacting with a collar 36 on the shaft 37, which serves as a support for the carrying gears 12 of the totalizer. The lever 30 is provided with an operating tail 38, having a slot 39 therein similar to the customary slots in the bottom of the swinging arms 32 of the Wahl totalizer, and said slot is designed to be operated upon by the master dog 40, customarily present in the Wahl machine. The lever 30 is located to the right of the lowest decimal place in the totalizer and we shall hereinafter call this decimal place the sub-units place of the totalizer, since this decimal place is one space to the right of the lowest or units decimal place of the totalizer.

We shall now describe the mechanism by means of which further operation of the machine is prevented in the event that the master dog 40 is operated in the sub-units place of the totalizer when said totalizer does not stand at zero.

Present in the Wahl machine and thoroughly described in the issued patents above referred to is a shaft, known as a rockshaft, which we have numbered 41 in this specification. This shaft has mounted on it a rocker 42, having a stud 43 mounted therein and is connected by a link 44 to a dog operating cam 45 mounted on a shaft 46, rotatably mounted in the framework. A slot 47 is cut in the operating cam 45 and serves to operate a roller 48, mounted in a lever 49 rigid to the master dog 40, which in turn is mounted on a shaft 50 rotatably mounted in the framework of the machine.

The rock shaft 41 has depending arms 51, having a rod 52 supported thereby, said rod being in the path of the fans 53 customarily present in the Wahl machine. Reference to the cited patents of Wahl will disclose the fact that there are ten of these fans 53, one for each of the nine digit keys and one connected to the 0 key. Each of the fans has cut into its surface a series of ratchet teeth 54 on the upper side and a second series of ratchet teeth 55 on the lower side. The ratchet teeth 54 are adapted to be acted on by the front full stroke pawl 56, and the ratchet teeth 55 are adapted to be acted on by the back full stroke pawl 57. The front full stroke pawl 56, being in engagement with the teeth 54 during the down stroke of the digit key, prevents any upward motion of the key until the down stroke has been completed and the back full stroke pawl 57 is in engagement with the teeth 55 on the up stroke of the digit key and prevents any downward motion of said key until the up stroke has been completed.

The rockshaft 41 has rigid with it an operating arm 58 which by its action on an

arm 59 rigid with the back full stroke pawl 57 holds said pawl out of engagement with the teeth 55 during the downstroke of the key. At the completion of the downstroke of the key, the rockshaft 41 turns in a counterclockwise direction (Fig. 5) and the arm 58, by its action on an arm 60, rigid with the front fullstroke pawl 56, serves to hold the latter out of engagement with the teeth 54 on the upstroke of the key. The mechanism by which these changes are accomplished is thoroughly described in the cited patent to Wahl and therefore need not be described in this place. It will be sufficient for an understanding of our present invention to note that during the downstroke of the key and consequent rotating of the master wheel 61 a differential amount, the front full stroke pawl 56 is held in the position shown in Fig. 5, and on the up stroke of the digit key the front full stroke pawl 56 is withdrawn from the teeth 54 and the back full stroke pawl 57 is thrown into engagement with the teeth 55. Reference to the cited patent to Wahl will further disclose that on the first part of the downstroke of any of the digit keys the master dog 40 is rotated in a clockwise direction and remains in this position until the downstroke of the key is completed, this motion of the master dog being provided for by the concentric surfaces of the slot 47. At the completion of the downstroke the master dog suddenly returns to its normal position, shown in Fig. 1, and during the upstroke of the key remains in such position. Extending from the master dog 40 and rigid with it is the truck lock 62, which engages with the teeth 63 of a rack 64 rigid to the lower side of the truck 11. The truck lock is for the purpose of preventing any motion of the typewriter carriage and its attached totalizer during the rotation of the master wheel or, what amounts to the same thing, during the downstroke of any of the digit keys. If from any reason the master dog 40 is prevented from returning to its original position upon its completion of the downstroke of any of the digit keys, then by reason of the engagement of the slot 47 with the roller 48 the rockshaft 41 will be prevented from returning to its original position and consequently the front fullstroke pawl 56 will remain in engagement with the teeth 54 of the fan 53, and further motion of the attached digit key will be prevented. Also further motion of the truck 11 relative to the master wheel will be prevented by the truck lock 62. When this condition obtains, the calculating machine is totally locked against further movement, since the digit key cannot rise and the truck 11 is also held immovable by reason of the truck lock 62.

In order to prevent the return of the

master dog to its original position, when any of the fans 53 are operated in the sub-units place of the totalizer when the totalizer does not stand at zero, we have provided a back arm 65 on the operating tail 38. Obviously if the lever 30 is held in its elevated position (shown in Fig. 5), the master dog 40 cannot return to its normal position upon the completion of the down-stroke of the key. Consequently, if it is attempted to operate any of the fans in the sub-units place of the totalizer when the totalizer does not stand at zero, then the calculating machine will be completely locked up and the attention of the operator will be called to the fact that the machine is being improperly operated.

The mechanism of the star or clear signal printing type bar 66 need not be described in detail further than to note that this bar is one of the ordinary printing type bars of the Remington machine, preferably the bar which prints 0 in its normal position. This bar is operated by the zero digit key 67 and serves to print zero when operated under normal conditions. In short, the star type is the upper case character on the type bar which, in lower case, prints the zero.

As previously noted, the zero digit key is connected to one of the fans 53 and therefore it is convenient to make this zero digit key print the characteristic mark for a clear signal when said key is operated while the shift key of the typewriter is depressed.

The operation of the machine in extracting a total is as follows: By means of the customary gear shift (not shown) the master wheel 61 is placed in its subtraction position and the number appearing on the totalizer is copied out. This results in subtracting this number from the totalizer. If this subtraction has been done correctly, the totalizer will stand at zero and the master wheel will be in contact with the totalizer in the sub-units place. The shift key of the typewriter is then operated, thus throwing the type bar 66 into its shift position, and the key 67 is then operated. This will result both in printing the star and in rocking the master dog 40 in a counterclockwise direction (Fig. 5). If the totalizer stands at zero, the latch 29 will then be held in a position not to engage the lever 30, and this lever will, under the influence of the spring 33, return to its normal position, when the master dog 40 is returned to its normal position upon the completion of the downstroke of the key 67. However, if the totalizer does not stand at zero, then the latch 29 will be in a position to engage the lever 30 and hold said lever in an elevated position. The back arm 65 of the tail 38 will then prevent the return of the master dog 40 to its normal position on the com-

pletion of the downstroke of the key 67, and the machine will be locked up, as previously noted, thus calling the attention of the operator to the fact that an incorrect total has been printed on the paper.

In order to provide means for restoring the machine to service under these conditions, we have provided the lever 25 with a finger piece 68, which project through the totalizer side plate 69. In the event that the machine has become locked up through the printing out of a wrong total, then the fingerpiece 68 may be pulled towards the front of the totalizer, thereby manually unlatching the lever 30. This will at once return to its normal position, thereby permitting the return of the master dog 40 to its normal position, which in its turn will permit the return of the digit key 67 to its normal position. The master wheel will then be thrown into addition and the incorrect number just printed on the worksheet will be reinserted into the totalizer, thus restoring the totalizer to its condition before the erroneous total was extracted therefrom. The erroneous total appearing upon the paper is then erased, the master wheel returned to its subtracting position and the correct total printed out. This will result in the return of the totalizer to zero, and when the key 67 is operated in the sub-units place, thus printing a second star over the star previously printed, it will return to its normal position without interference. The totalizer of the machine will then be clear and ready for a new computation.

It may be urged that the presence of a star on the worksheet opposite a total does not necessarily mean that the correct total has been printed from the machine, since, as just noted, one may print an incorrect total, then print the star, which will result in the machine becoming locked up. The machine can then be released by manual operation of the finger piece 68 and a new computation started with the totalizer not standing at clear. However, we do not consider that this objection is at all material, since an adding machine of the Wahl type can always be intentionally misoperated, as, for example, by inserting a piece of paper between the type bar and the platen, whereby a number may be inserted in the machine and not be printed on the platen at all. We do not aim in our present invention to guard against malicious misoperation. The person who operates a Wahl machine is more interested than anyone else in operating the machine correctly, since the operator is the person who will have to search for errors when the same have been discovered. Consequently, it is sufficient for our present purpose to warn the operator at the time an incorrect total is extracted from the machine, and to this end our here-

in described invention is well adapted, since upon attempting to print a star in the sub-units place when the totalizer is not clear, the machine will become locked up and can 5 only be restored to working condition by intentional operation of the fingerpiece 68. It will be noted that by the present invention the condition of the register is tested by operating the key 67 in the sub-units position. If when this key is depressed it immediately returns to normal position without locking up the machine then the operator is thereby notified that the totalizer is clear, but if when it is operated the key remains 15 in its depressed position and locks up the machine then the operator is by that condition notified that the machine is not clear. The star type is used merely to indicate or to assure that this key was operated 20 in the sub-units position. The operator is required to depress this key whenever the total is copied, and the printing of the star in the next space immediately following the number, shows that the key was depressed 25 at that time. It will, of course, be understood that any other suitable means might be employed for assuring that this particular key was operated at that particular time. Many advantages result from our improved mechanism herein described, among which we may note that it may be applied 30 to machines already in existence by the simple expedient of supplying them with a totalizer equipped with the mechanism shown 35 in the sub-units place and changing the type in the zero type bar so that said type will print a star or other characteristic clearance mark when thrown to its shift position. Another advantage resulting from our improved mechanism is its extreme simplicity, 40 since it consists in the addition of but a few simple parts to the ordinary totalizer mechanism of the Wahl machine. It will be further observed that totalizers equipped 45 with our clear signal device and totalizers not so equipped may be operated on the same machine without interference. It is only necessary to remember not to attempt to print the star in the sub-units place of a 50 totalizer not equipped with our improved signal. As a matter of fact, it will be impossible to operate the star printing key in the sub-units place of any totalizer not equipped with our improved clear signal, 55 since the Wahl totalizers are customarily provided with an extension of the side plate 69, which registers with the master dog 40 when the totalizer is in the sub-units position and thus prevents the rotation of said dog. Therefore, in operating a machine 60 equipped with ordinary Wahl totalizers and Wahl totalizer equipped with our herein described invention, the operator is automatically prevented from misoperating the machine. 65

In our herein described structure, which is our preferred form, we have described the star printing signal as being placed on the zero key and printed by throwing said key into its shift position. However, it is by no 70 means necessary that the zero key be employed. Any of the other digit keys might be employed for this purpose, or indeed an extra fan 53 might be put into the actuator and connected to the special key which 75 printed only the star, thus obviating the necessity of operating the typewriter in its shift position when it was desired to print the characteristic mark for the clear signal. Wahl actuators equipped with eleven fans 80 are described in the patent to Arthur F. Poole, No. 1,274,572, August 6, 1918, the extra key in the Poole patent being numbered 16 in Fig. 5 thereof. It is to be further noted that said key is provided with an 85 interlock which permits its operation only when the totalizer or decimal carriage has reached a predetermined position, and this interlock can be advantageously employed to lock the star printing key so that said key 90 can be operated only in the sub-units place of the totalizer. We have found it advantageous to make the prong 20 of the comb 18 engaging the gear wheel 16 in the units order slightly 95 longer than the other prongs which engage the gear wheel 16 in the higher order. This is for the purpose of throwing the entire load of the spring 21 upon the wheel in the units order, since in this event the friction 100 due to the spring 21 will be exerted only on the units wheel, and since the units wheel is never moved through a process of carrying, there will always be available the power of the master wheel 61 as transmitted through 105 the intermediate gears 12 and 14 to move the wheel 15 in the units order. As a matter of experience we have found that the friction of the comb 18 on the wheel 16 of the totalizer is immaterial, since the cam may rest 110 on any of the gears 16 without interfering with the operation of the totalizer. However, we consider the arrangement of insuring that the cam 18 be supported by the gear wheel 16 of the units order to be preferable. It is also to be understood that the short teeth 17 are such a length as to not interfere with the driving action of the gear 14. This feature has been thoroughly explained in the copending application of 120 Arthur F. Poole, Serial No. 757,934, filed March 31, 1913, now Patent No. 1,311,710, dated July 29, 1919, to which reference may be had for further description of the action of the comb 18 on the short teeth 17. 125

Many improvements and variations may be made in the precise mechanism herein described without departing from the spirit of our invention, since we claim:

1. In a calculating machine, the combina- 130

tion of a totalizer, a zero determining device in said totalizer, a key adapted to print a characteristic mark, and mechanism connecting said key with said totalizer to permit a partial operation sufficient to print said mark, but to prevent a complete operation of said key in the event said totalizer does not stand at zero.

2. In a calculating machine, the combination of a totalizer, a key to print a characteristic mark indicative of a zero condition of said totalizer, and means connecting said key and said totalizer to permit a partial stroke sufficient to print said mark, but to prevent a full stroke of said key in the event said totalizer does not stand at zero.

3. In a calculating machine, the combination of a key adapted to print a characteristic mark, means to compel a complete stroke of said key when once a stroke has been initiated, a totalizer, and means connecting said key and said totalizer to prevent a complete stroke of said key in the event that said totalizer does not stand at zero.

4. In a calculating machine, the combination of a totalizer, a key adapted to print a characteristic mark indicative of the standing of said totalizer at zero, a full stroke mechanism associated with said key, said full stroke mechanism being adapted to be in one position upon the down stroke of said key and in another position on the up stroke of said key, and being changed from one position to another during the cycle of the stroke of said key, and means preventing the change of said full stroke mechanism from one position to another during the operation of said key in the event that said totalizer does not stand at zero.

5. In a calculating machine, the combination of a totalizer, a zero determining device in said totalizer, a set of keys adapted to insert a number in said totalizer, a traveling member whereby the action of said keys on said totalizer may be determined, a special key adapted to print a characteristic mark, and a mechanism connecting said key with said totalizer to prevent the travel of said traveling member in the event that said totalizer does not stand at zero at the time when said special key is operated.

6. In a calculating and printing machine, the combination with a totalizer and means for operating the same, of a key for printing a characteristic mark, connections from said key into the totalizer, and a latch in said

totalizer to permit or prevent the return motion of said key depending on the condition of the totalizer.

60

7. In a calculating and printing machine, the combination with a totalizer, key actuated means for printing numbers and adding them into said totalizer and for printing the total and subtracting it from said totalizer, locking devices operated by said key actuated means, and means controlled by said totalizer to prevent said locking means from returning to unlocking position at a certain key stroke in case the totalizer does not stand at zero.

65

8. In a calculating machine, the combination with a totalizer and means for operating the same, of a hand operated device and means controlled by the state of the totalizer for preventing the return of said device to normal position after an operation thereof in case said totalizer does not stand at zero.

70

9. In a calculating machine, the combination with a traveling carriage, a totalizer, and means for operating said totalizer, of a hand operated device, means controlled by the state of the totalizer for preventing the return of said device to normal position after an operation thereof in case said totalizer does not stand at zero, and means for assuring that said device was operated when said carriage stood in a certain position.

75

10. In a calculating machine, the combination with a totalizer and means for actuating the same, of a key for printing a characteristic mark when said totalizer stands at zero and also when said totalizer does not stand at zero, and means whereby an operation of said key locks an essential part of the machine in case said totalizer does not stand at zero at the time when said key is operated.

80

11. In a calculating machine, the combination with a totalizer and means for actuating the same, of a device which can be operated by hand when said totalizer stands at zero and also when said totalizer does not stand at zero, and means whereby an operation of said device immediately locks an essential part of the machine in case the totalizer did not stand at zero when said device was operated.

85

In witness whereof we have hereunto subscribed our names.

HYMAN GOLBER,
ARTHUR F. POOLE.

90
